Adam C. Fisher
ATTORNEY

UNITED STATES PATENT OFFICE.

SAMUEL F. SWANTEES, OF ST. LOUIS, MISSOURI.

RIBBED UNDERFLAP FOR UNDERGARMENTS.

Application filed August 2, 1922. Serial No. 579,149.

To all whom it may concern:

Be it known that I, SAMUEL F. SWANTEES, a citizen of the United States, residing in the city of St. Louis and State of Missouri, have invented new and useful Improvements in Ribbed Underflaps for Undergarments, of which the following is a specification, reference being had to the accompanying drawings.

10 This invention is in the way of a ribbed under-flap for the crotch or seat opening of undergarments, and the object is to provide a flap for this purpose having ribs, plait, plicatures or corrugations extending horizontally across the flap, this said ribbed formation being intended and designed to prevent the flap from rolling or buckling into the crotch of the wearer, as is the case with garments employing the ordinary plain flap.

15 In the drawing:

Figure 1 is a back view of an undergarment or "union suit" equipped with this improved under flap, the ordinary outer flap being omitted but its location being indicated in dotted lines.

20 Figure 2 is a similar view, showing the ordinary outer flap buttoned in place, the location and outline of the improved, ribbed underflap being indicated in dotted lines.

25 In describing the improvement it is described as though the undergarment to which it is attached were worn by a person standing upright.

30 35 In carrying out this invention, I provide for the seat opening 1 of an under garment 2, an improved under flap 3 attached in con-

ventional manner and form to the under garment. This improved under flap is made of any suitable cloth or fabric, the same being formed, however, with ribs, corrugations, folds, creases or plaits 4 extending substantially horizontally across the flap. The gist of the invention lies in this horizontal ribbed formation of the under flap 3, whereby the flap is caused always to stand out from the body of the wearer, along the horizontal lines of the ribs, plaits or flexions described, and is prevented from rolling or buckling.

40 Any structure whereby the flap is caused to relatively resist folding, rolling or bending on the longitudinal lines of the garment, would come within the spirit of this invention as defined in the appended claim.

I claim:

45 An undergarment provided at the back with a seat opening, an outer flap extending across the seat opening and covering the same at the exterior of the garment and buttoned to the same, and an interior oppositely disposed flap extending across the seat opening and covering the same interiorly of the garment and widened between its upper and lower ends to form a lateral extension at the free edge, said inner flap being ribbed horizontally throughout the entire width of the flap, whereby the flap is caused to maintain its normal position and resist folding, rolling or bending about its longitudinal axis.

50 55 60 65 SAMUEL F. SWANTEES.
